Herbert Monroe Conn, Jr., Royal Oak, Mich., assignor to
General Motors Corporation, Detroit, Mich., a corpora-
tion of Delaware

Application March 22, 1955, Serial No. 35,152

Term of patent 7 years

(Cl. D14—3)

The single figure is a side elevation of an automobile incorporating my new design.

The characteristic feature of my design for the automobile disclosed resides in the configuration of the molding strip that runs from the base of the windshield post laterally to the rear of the automobile.

I claim:

The ornamental design for an automobile, substantially as shown and described.
